US00D996420S

(12) **United States Design Patent** (10) **Patent No.:** **US D996,420 S**
He et al. (45) **Date of Patent:** **** Aug. 22, 2023**

(54) **SMARTWATCH**

(71) Applicant: **SHENZHEN DO INTELLIGENT TECHNOLOGY CO., LTD.**,
Guangdong (CN)

(72) Inventors: **An He**, Shenzhen (CN); **Yuanyuan Chen**, Guangdong (CN)

(73) Assignee: **SHENZHEN DO INTELLIGENT TECHNOLOGY CO., LTD.**, Shenzhen (CN)

(**) Term: **15 Years**

(21) Appl. No.: **29/836,368**

(22) Filed: **Apr. 26, 2022**

(30) **Foreign Application Priority Data**

Feb. 15, 2022 (CN) 202230072302.5

(51) **LOC (14) Cl.** **14-02**

(57) **CLAIM**

The ornamental design for a smartwatch, as shown and described.

DESCRIPTION

FIG. 1 is a front and right side perspective view of a smartwatch showing our new design;

FIG. 2 is a rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings represent portions of the smartwatch that form no part of the claimed design.

1 Claim, 8 Drawing Sheets
